CLAIM

I claim the ornamental design for a microbiological bead separation magnet holder or similar article, as shown and described.

DESCRIPTION

FIG. 1 is a perspective view of the microbiological bead separation magnet holder.

FIG. 2 is a plan view of the magnetic tube holder.

FIG. 3 is a side view of the magnet holder.

FIG. 4 is a side view of the opposite side of that shown in FIG. 3.

FIG. 5 is a rear view of the magnet holder; and,

FIG. 6 is a bottom view of the magnet holder.
